(57) **CLAIM**

The ornamental design for a target box for a ball throwing game, as shown and described.

DESCRIPTION

FIG. 1 is a perspective view of a target for a ball throwing game showing our new design;

FIG. 2 is a perspective view thereof, shown in folded position;

FIG. 3 is a front elevational view of FIG. 1;

FIG. 4 is a left side elevational view of FIG. 1;

FIG. 5 is a top plan view of FIG. 1;

FIG. 6 is a rear elevational view of FIG. 1;

FIG. 7 is a right side elevational view of FIG. 1; and,

FIG. 8 is a perspective view thereof, shown in unfolded position and the tray removed for clarity of illustration.

The broken lines in the drawing indicates fold lines.
